US00D745022S

(12) **United States Design Patent**
McCleary et al.

(10) **Patent No.:** US D745,022 S
(45) **Date of Patent:** ** Dec. 8, 2015

(54) **IMAGING SYSTEM DISPLAY SCREEN WITH GRAPHICAL USER INTERFACE**

(71) Applicant: **Karl Storz Imaging, Inc.**, Goleta, CA (US)

(72) Inventors: **James McCleary**, Los Angeles, CA (US); **Marc R. Amling**, Santa Barbara, CA (US); **Angeli Mancuso Ruiz**, Santa Barbara, CA (US); **Jeff Watson**, Goleta, CA (US); **Lee D. Holoi**, Santa Barbara, CA (US); **Jean Nisbet**, Goleta, CA (US)

(73) Assignee: **Karl Storz Imaging, Inc.**, Goleta, CA (US)

(**) Term: **14 Years**

(21) Appl. No.: **29/441,121**

(22) Filed: **Dec. 31, 2012**

(51) LOC (10) Cl. **14-04**

(52) U.S. Cl.

USPC **D14/486**

(58) **Field of Classification Search**

USPC D14/485-495

CPC G06F 3/048; G06F 3/04817; G06F 3/0482

(57) **CLAIM**

The ornamental design for an imaging system display screen with graphical user interface, as shown and described.

DESCRIPTION

The FIGURE is a front view of the imaging system display screen with graphical user interface in accordance with the new design.

The broken line showing of the display screen or portion thereof and other elements are for illustrative purpose only and form no part of the claimed design.
